CLAIM

I claim the ornamental design for a gaming machine, as shown and described.

DESCRIPTION

FIG. 1 is a front perspective view of a gaming machine showing my new design according to a first embodiment; FIG. 2 is a right side perspective view thereof; FIG. 3 is a top plan view thereof;

FIG. 4 is a front perspective view of a gaming machine showing my new design according to a second embodiment; FIG. 5 is a right side perspective view thereof; and, FIG. 6 is a top plan view thereof.

The dashed broken lines in the figures illustrate portions of the gaming machine that form no part of the claimed design.
